BRANKO LAZICH, OF EDGEWOOD, PENNSYLVANIA, ASSIGNOR TO THE UNION SWITCH & SIGNAL COMPANY, OF SWISSVALE, PENNSYLVANIA, A CORPORATION OF PENNSYLVANIA

APPARATUS FOR THE CONTROL OF HIGHWAY CROSSING SIGNALS

Application filed May 12, 1931, Serial No. 536,725. Renewed March 24, 1932.

My invention relates to apparatus for the control of highway crossing signals, and has for an object the provision of means controlled by a train approaching a highway for starting the operation of the signal at substantially the same interval of time before the train reaches the highway regardless of the speed of the train.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a stretch A of railway track over which traffic normally moves in the direction indicated by the arrow. These track rails are divided, by means of the usual insulated joints 2, into a plurality of successive track sections B—C, C—D and D—E. Each track section is provided with the usual track circuit comprising a suitable source of current, such as a track battery 3, connected across the rails adjacent the entrance end of the section, and a track relay, designated by the reference character T with a suitable distinguishing exponent, connected across the rails adjacent the exit end of the section. Interposed between track relay T^a and rail 1^a in the track circuit for section B—C is a front contact 4 of track relay T^b, the function of which will become apparent as the description proceeds.

Track section C—D is intersected by highway H at a point somewhat in rear of the point D, and located adjacent the intersection is a highway crossing signal S, which, as here shown, is in the form of an electric bell. The signal S is controlled by a relay F, the circuit for this signal being from terminal B of a suitable source of current not shown in the drawing, through front contact 5 of relay F, and the operating mechanism of signal S to the other terminal C of the source. Relay F is normally deenergized, so that this signal will normally be silent but will operate whenever relay F becomes energized.

Relay F, in turn, is controlled by a slow

acting relay G, by track relay T^b, and by a time measuring device which is designated as a whole by the reference character J.

As here shown, the time measuring device J comprises a rotatable shaft 6 which is journaled at its ends in suitable fixed bearing blocks 26. The shaft 6 normally occupies the position in which it is illustrated in the drawing, but it is arranged to at times be moved away from this position in a counter-clockwise direction, and at other times restored to this position, in accordance with certain conditions to be described herein-after, by means of a reversible motor M having an armature 7 and a field 8. As here shown, the armature 7 of the motor M operates a worm 9 which drives a worm wheel 10 fixed to the shaft 6, but it will be readily understood that any other suitable form of mechanism for driving the shaft 6 by the motor M may be employed. Mounted on the shaft 6 is an arm 11 which is arranged to operate two circuit controllers K and L. The circuit controller K, in the form here shown, comprises two normally closed contacts 12—13 and 14—15, and a normally open contact 12—16, while the circuit controller L comprises a normally closed contact 17—18. As soon as the shaft 6 starts to rotate in a counter-clockwise direction from the position shown, which position I will term its "normal" position, the arm 11 moves away from the contact finger 12, and the contact fingers 12 and 14 then move toward the left, due to an initial bias, thereby opening contacts 12—13 and 14—15, and closing contact 12—16. When the shaft 6 has rotated in a counter-clockwise direction to what I will term its "ultimate position" the arm 11 then engages the contact finger 17 of circuit controller L and opens contact 17—18.

The time measuring device J also comprises a sleeve 19 which is free to turn on the shaft 6. A coil spring 20, having one end secured to a fixed abutment and the other end secured to the sleeve 19, biases the sleeve 19 to its normal position on the shaft in which position a pin 21 carried by the sleeve 19 engages a pin 22 carried by the shaft. The pins 21 and 22, in addition to serving

- as a stop for the sleeve, also serve as a driving connection between the shaft and the sleeve when the shaft is rotated in a counter-clockwise direction, the resultant rotation of the sleeve acting to wind the coil spring 20. Rigidly attached to the sleeve 19 is a ratchet wheel 23, and cooperating with this ratchet wheel is a pawl 24, which is pivoted for rotation about an axis indicated at 24^a in the drawing. The pawl 24 is biased by gravity into engagement with the ratchet wheel, but is arranged to be at times withdrawn from engagement with the ratchet wheel by means of a solenoid 25 which operates a plunger 25^a pivotally attached to the pawl. It will be seen that when the sleeve 19 is rotated in a counterclockwise direction, the pawl 24 will drop behind the successive teeth on the ratchet wheel, and will thus maintain the sleeve in the extreme position to which it is moved in this direction, until the solenoid 25 is subsequently energized to withdraw the pawl from engagement with the ratchet wheel.
- 26 Also rigidly attached to the sleeve 19 is a contact arm 27 which controls a variable resistance R. As here shown, the resistance R is provided with a plurality of taps designated by the reference characters 28 to 36, 30 inclusive, which taps cooperate with the arm 27 in such manner that the portion of the total resistance which is connected between the arm and the tap 35 will be decreased as the arm consecutively engages these taps, but 35 that, when the arm engages the tap 36, which tap it will be noted is connected with the tap 28 by means of a wire 37, the total resistance will be connected between the arm and the tap 35.
- 40 The timing device further comprises a fixed resistance 38 which is at times connected in series with the field 8 of motor M as will be described hereinafter, and a centrifuge N. The centrifuge N is operatively connected with the motor M, and controls a contact 39—40 in such manner that this contact is closed except when the motor is rotating in either direction at a speed which exceeds a predetermined value.
- 45 Armature 7 of motor M is provided with a circuit which is controlled by track relays T^a, T^b and T^c, and by contact 17—18 of circuit controller L. This circuit is closed only when track relays T^a and T^b are both energized, track relay T^c is deenergized, and contact 17—18 of circuit controller L is closed, and passes from terminal B through back contact 41 of track relay T^c, wire 48, front contact 49 of track relay T^b, wire 50, 50 front contact 51 of track relay T^a, wire 52, contact 17—18 of circuit controller L, wires 56 and 53, armature 7 of motor M, wires 54 and 55, front contact 45 of track relay T^b, wire 46, and back contact 42 of track relay T^c to terminal C. Armature 7 of motor M

is also provided with another circuit which is controlled by track relays T^b and T^c and by contact 12—16 of circuit controller K, and which is closed only when track relays T^b and T^c are both deenergized, and contact 12—16 is closed. This latter circuit passes from terminal B through back contact 41 of track relay T^c, wire 48, back contact 49 of track relay T^b, wires 55 and 54, armature 7 of motor M, wires 53 and 70, contact 12—16 of circuit controller K, wire 71, back contact 45 of track relay T^b, wire 46, and back contact 42 of track relay T^c to terminal C. It will be noted from an inspection of the drawing that the current which is supplied to armature 7 when this latter circuit is closed flows through the armature in the opposite direction from that which is supplied to the armature when the first traced circuit for armature 7 is closed.

Field 8 of motor M is likewise provided with two circuits which are controlled by track relays T^b and T^c. The one circuit for field 8 includes fixed resistor 38, and is closed when track relay T^b is energized and track relay T^c is deenergized. This circuit passes from terminal B through back contact 41 of track relay T^c, wire 57, field 8 of motor M, wire 59, resistance 38, wire 60, front contact 61 of track relay T^b, wires 62 and 46, and back contact 42 of track relay T^c to terminal C. The other circuit for field 8 of motor M includes the portion of the variable resistance R which is connected between the arm 27 and tap 35 at the time this circuit becomes closed, this circuit being completed when track relays T^b and T^c are both deenergized. This latter circuit for field 8 passes from terminal B through back contact 41 of track relay T^c, wire 57, field 8, wire 59, tap 35 of resistance R, the portion of resistance R which is connected between tap 35 and arm 27, arm 27, wire 72, back contact 61 of track relay T^b, wires 62 and 46, and back contact 42 of track relay T^c to terminal C. It will be noted that the current supplied to field 8 when either of these circuits just traced is closed, flows through the field in the same direction.

It will be seen, therefore, that when track relay T^b is energized and track relay T^c is deenergized, the circuit first traced for field 8 of motor M including fixed resistor 38, and the circuit first traced for armature 7, are normally both closed; but that, when track relays T^b and T^c are both deenergized, the circuit last traced for field 8 of motor M, and the circuit last traced for armature 7, are normally both closed. The parts are so arranged and so proportioned that when the circuit first traced for field 8 of motor M and the circuit first traced for armature 7 are both closed, the currents which are then supplied to the field 8 and armature 7 over these circuits will be of such relative polarity

that the armature will operate in the direction to rotate shaft 6 away from its normal position in the counter-clockwise direction. It follows, therefore, that if a train enters section B—C and deenergizes track relay T^c when section C—D is unoccupied, so that track relay T^p is energized, motor M will start to rotate shaft 6 away from its normal position, and will continue to rotate shaft 6 away from its normal position until the train subsequently enters section C—D and deenergizes track relay T^p . When this happens, however, the direction of current flow through the armature will be reversed, while the direction of current flow through the field will be the same as when track relay T^p was energized, and motor M will therefore reverse and restore shaft 6 to its normal position.

It will be readily understood by anyone skilled in the art that if the strength of the current supplied to the armature of a motor of the type described remains constant, the speed of rotation of the armature will normally depend upon the strength of the field current, this speed being increased as the strength of the field current is decreased. It follows, therefore, that since the resistance 38 is fixed, the speed at which the motor rotates the shaft away from its normal position in the counter-clockwise direction will always be constant; but that, since the resistance R is variable, the speed at which the motor returns the shaft to its normal position will depend upon the value of the portion of this resistance which is included in the field circuit under these conditions and, hence, upon the distance away from its normal position in the counter-clockwise direction through which the shaft 6 had been rotated up to the instant that track relay T^p becomes deenergized, this speed being decreased as the position of the shaft away from its normal position is increased, except when the shaft has been rotated to its ultimate position in which arm 27 engages tap 36 and connects the total resistance in series with the field.

Solenoid 25 of timing device J is provided with a circuit which is closed when track relays T^p and T^c are both deenergized, and contact 12—13 of circuit controller K is closed. This circuit passes from terminal B through back contact 41 of track relay T^c , wire 48, back contact 49 of track relay T^p , wires 55 and 73, solenoid 25, wire 74, contact 12—13 of circuit controller K, wire 71, back contact 45 of track relay T^p , wire 46, and back contact 42 of track relay T^c to terminal C.

Relay G is provided with a circuit which is controlled by track relays T^p and T^c , and which passes from terminal B through back contact 41 of track relay T^c , wire 43, winding of relay G, wire 44, front contact 45 of track relay T^p , wire 46 and back contact 42 of track

relay T^c to terminal C. This circuit is closed when and only when track relay T^c is deenergized and track relay T^p is energized, and it will be apparent, therefore, that if section C—D is unoccupied when a train moving in the direction of the arrow enters section B—C, relay G will become energized and will subsequently remain energized until the train enters section C—D.

Relay F is provided with a circuit which passes from terminal B through the winding of relay F, wire 63, back contact 47 of relay G, wire 64, back contact 65 of track relay T^p , wire 66, contact 14—15 of circuit controller K, and wire 67 to terminal C. This circuit is also provided with a branch around contact 14—15 of circuit controller K which branch may be traced from wire 66 through wire 68, contact 39—40 controlled by centrifuge N, and wire 69 to terminal C. It will be apparent, therefore, that relay F will become energized when track section C—D is occupied provided contact 14—15 of circuit controller K is then closed, or in the event that motor M stops for any reason, so that contact 39—40 controlled by centrifuge N becomes closed.

As shown in the drawing track sections B—C, C—D, and D—E are all unoccupied so that track relays T^c , T^p and T^e are all energized. Relay G is therefore deenergized and solenoid 25 is also deenergized. Shaft 6 and sleeve 19 both occupy their normal positions. Contact 17—18 of circuit controller L, and contacts 12—13 and 14—15 of circuit controller K are therefore closed, while contact 12—16 of circuit controller K is open. Both circuits for armature 7 of motor M are open at back contacts 41 and 42 of track relay T^c , and both circuits for field 8 of motor M are likewise open at these contacts. Motor M is therefore deenergized. Relay F is also deenergized, the circuit for this relay being open at front contact 65 of track relay T^p . Since relay F is deenergized, signal S is silent.

In explaining the operation of the apparatus as a whole, I will assume that with the parts in the positions just described, a train moving in the direction of the arrow traverses the stretch A. When the train enters section B—C, it deenergizes track relay T^c , and since track relay T^p is then energized, relay G becomes energized and opens its back contact 47. This interrupts the circuit previously traced for relay F, and hence insures that relay F will not become energized and cause signal S to operate as long as section C—D is unoccupied. The deenergization of track relay T^c also completes the circuit previously traced for field 8 of motor M including resistance 38, as well as the circuit previously traced for armature 7 including contact 17—18 of circuit controller L, so that motor M now starts to rotate shaft 6 away from its

normal position in the counter-clockwise direction in the manner previously described, thereby rotating sleeve 19 in the same direction, and hence rotating the arm 27 in the direction to decrease the portion of the resistance R which is connected between the contact arm 27 and tap 35. As soon as shaft 6 starts to rotate, arm 11 moves away from contact finger 12 thus permitting circuit controlled K to open its contacts 12-13 and 14-15, and to close its contact 12-16. The operation of this circuit controller, however, has no immediate effect on the remainder of the apparatus under these conditions. Motor M will now continue to rotate shaft 6 away from its normal position in the counter-clockwise direction until the train enters section C-D and deenergizes track relay T^D, unless the train remains in section B-C for an abnormally long interval of time, under which conditions, armature 7 will become deenergized when the shaft has been rotated to its ultimate position, as will be explained more fully hereinafter. When track relay T^D becomes deenergized, the opening of its front contact 61 interrupts the circuit over which field 8 of motor M was previously supplied with current, and the opening of its front contact 49 interrupts the circuit over which armature 7 was previously supplied with current, while the closing of its back contacts 49 and 45 completes the circuit for armature 7 including these contacts, and the closing of its back contact 61 completes the circuit for field 8 including this contact. Motor M therefore now reverses and starts to restore shaft 6 to its normal position. The opening of front contact 45 of track relay T^D also deenergizes relay G. It should be pointed out, however, that relay G is sufficiently slow releasing so that it will not close its back contact 47 during the interval of time that contact 39-40 controlled by centrifuge N is normally closed while motor M is reversing, thus preventing relay F from becoming energized over its branch circuit including contact 39-40 under these conditions, and hence preventing signal S from operating. If, however, the motor should stall, or fail to become energized for any reason, so that contact 39-40 remained closed for a longer interval of time than that required for relay G to become deenergized, then as soon as relay G had become deenergized, relay F would become energized and would complete the circuit for signal S, thus preventing the dangerous condition which might exist under these conditions if contact 47 of relay G and contact 39-40 were not included in the control of relay F. Furthermore, the opening of front contact 4 of track relay T^D opens the track circuit for section B-C including track relay T^C, thus preventing track relay T^C from picking up as long as track relay T^D is deenergized, even though the train passes com-

pletely out of section B-C. As pointed out hereinbefore, the speed at which the motor returns the shaft 6 to its normal position when track relays T^D and T^C are both deenergized, depends upon the portion of the resistance R which is included in the circuit for field 8 when track relay T^D becomes deenergized. The parts are so proportioned, that if the train is traveling at its maximum speed while traversing section B-C, then at the instant that track relay T^D becomes deenergized, arm 27 will engage tap 29 of this resistance, and it will be seen, therefore, that under these conditions, the speed at which motor M returns shaft 6 to its normal position will depend upon the value of the portion of the resistance R which is connected between the taps 29 and 35, it being understood that the pawl 24 and ratchet wheel 23 holds the sleeve 19 in the extreme position to which it was previously rotated before track relay T^D became deenergized. Since the portion of the resistance R which is included between the taps 29 and 35 is a large percentage of the total resistance, it follows that motor M will rotate at nearly its maximum speed under these conditions, thereby restoring the shaft 6 to its normal position quickly. When the shaft 6 reaches its normal position, contact 12-16 of circuit controller K becomes opened and contacts 12-13 and 14-15 become closed. The opening of contact 12-16 interrupts the circuit which was previously closed for armature 7, thus stopping motor M, while the closing of contact 14-15 completes the circuit previously traced for relay F, so that relay F now picks up and causes signal S to operate. Furthermore, the closing of contact 12-13 completes the circuit previously traced for solenoid 25, and solenoid 25 therefore becomes energized and withdraws pawl 24 from engagement with the ratchet wheel 23. Spring 20 then returns sleeve 19 to its normal position on shaft 6, in which position pin 22 engages pin 21 as shown in the drawing. When the train enters section D-E, track relay T^E becomes deenergized and opens its front contact 51. This interrupts the circuit for armature 7 including this contact, and insures that armature 7 will not become energized when track relay T^D subsequently picks up due to the train having passed completely out of section C-D. When the train has passed completely out of section C-D, the opening of back contact 65 of track relay T^D interrupts the circuit for relay F, and relay F therefore becomes deenergized and deenergizes signal S, so that signal S now stops operating. Furthermore, the closing of front contact 4 of track relay T^D completes the track circuit for section B-C, and track relay T^C now picks up and opens its back contacts 41 and 42. This interrupts the circuit which was previously closed for field 8 of motor M, as well

as the circuit which was previously closed, and field 8 and solenoid 25 therefore now both become deenergized. When the train has passed completely out of section D—E, track relay T^p picks up, and the parts are then restored to the positions in which they are illustrated in the drawing.

If a train traveling at a somewhat slower speed traverses stretch A, the parts will function in the manner just described with the exception that at the instant the train enters section C—D and deenergizes track relay T^p to reverse motor M, arm 27 will have moved past tap 29 of resistance R and into engagement with tap 30. The speed at which motor M returns shaft 6 to its normal position under these conditions will therefore depend upon the value of the portion of resistance R which is connected between the taps 30 and 35, and since this value is less than the value of the portion which is connected between taps 29 and 35, this speed will be slower than the speed at which the shaft was returned to its normal position when the train was traveling at its maximum speed. As a result, a longer interval of time will be required for shaft 6 to reach its normal position under these conditions, and since signal S does not start to operate until the shaft has reached its full normal position and closed contact 14—15 of circuit controller K to energize relay F as previously described, it follows that with the slower speed train, signal S will not start to operate as soon after the train has entered section C—D as it did with the higher speed train.

It will be apparent, therefore, from the foregoing, that the slower the speed of the train, the longer will be the time interval which will elapse before signal S will start to operate after the train has entered section C—D, and it follows that by properly proportioning the parts, the signal may be made to operate at substantially the same interval of time before the train reaches the highway regardless of the speed of the train. For example, the parts may be so proportioned that the signal S will start to operate substantially 20 seconds before the train reaches the highway H regardless of the speed at which the train is approaching the highway.

As pointed out hereinbefore, if a train which has entered section B—C remains in this section for an abnormally long interval of time for any reason, as would be the case, for example, if the train stopped in the section, motor M will continue to rotate shaft 6 in the counter-clockwise direction until the shaft has been rotated to its ultimate position. When this has happened, contact 17—18 of circuit controller L will become opened and will interrupt the circuit which was previously closed for armature 7, thus deenergizing armature 7, and hence preventing further rotation of the shaft 6 in the counter-

clockwise direction. Shaft 6 will then remain in its ultimate position until the train subsequently enters section C—D and deenergizes track relay T^p. When this happens, motor M will reverse as previously described, and since arm 27 now engages tap 36, all of the resistance R will be connected in the circuit for field 8, with the result that the motor will restore the shaft 6 to its normal position under these conditions at its maximum speed. Relay F will therefore become energized and cause signal S to operate shortly after the train has entered section C—D, thus insuring that a warning indication will be given in ample time to protect users of the highway even though the train speeds up to its maximum speed before it reaches the highway.

Although I have herein shown and described only one form of apparatus for the control of highway crossing signals embodying my invention, it is understood that various changes and modifications may be made therein within the scope of the appended claims without departing from the spirit and scope of my invention.

Having thus described my invention, what I claim is:

1. In combination, a stretch of railway track intersected by a highway, a highway crossing signal located adjacent the intersection, a member normally occupying one position, means for moving said member away from said one position at a constant speed during the time interval required for a train approaching said highway to traverse a fixed distance, means effective when the train has traversed said fixed distance for restoring said member to said one position at a speed which depends upon the position to which said member was previously moved, and means responsive to the position of said member for controlling said signal.

2. In combination, a stretch of railway track intersected by a highway, a highway crossing signal located adjacent the intersection, a member normally occupying one position, means for moving said member away from said one position at a constant speed during the time interval required for a train approaching said highway to traverse a fixed distance, means effective when the train has traversed said fixed distance for restoring said member to said one position at a speed which depends upon the position to which said member was previously moved, and means effective when said member has been restored to said one position for setting said signal into operation.

3. In combination, a stretch of railway track intersected by a highway, a highway crossing signal located adjacent the intersection, a member normally occupying one position, means effective while a train approaching said intersection is traversing a fixed dis-

5 tance for moving said member away from said one position at a constant speed, means effective when the train has traversed said fixed distance for restoring said member to said one position at a variable speed which depends upon the distance through which said member was previously moved, means effective when said member has been restored to said one position for setting said signal 10 into operation, and means effective when said train has passed the intersection for stopping the operation of said signal.

15 4. In combination, a stretch of railway track intersected by a highway, a highway crossing signal located adjacent the intersection, a member normally occupying one position, means effective while a train approaching said intersection is traversing a fixed distance for moving said member away from said one position at a constant speed, means effective when the train has traversed said fixed distance for restoring said member to said one position at a variable speed which depends upon the distance through which said member was previously moved, said speed being decreased as the distance through which said member was previously moved is increased, and means controlled in part by said member for setting said signal into 20 operation when said member is restored to said one position.

25 5. In combination, a stretch of railway track intersected by a highway, a member normally occupying one position, means controlled by a train approaching the highway for rotating said member away from said one position in one direction at a constant speed through a variable distance which depends upon the speed of the train between a first fixed point and a second fixed point, means effective when the train passes said second point for rotating said member in the opposite direction to restore said member to said one position, means controlled by said member and responsive to the distance away from said one position through which said member was moved for controlling the speed at which said member is restored to said one position, a highway crossing signal located adjacent said intersection, and means for setting said signal into operation when said member is restored to said one position, the parts being so proportioned that said member will be restored to said position at substantially the same interval of time before the train reaches the highway regardless of the speed of the train.

30 6. In combination, a stretch of railway track intersected by a highway, a member normally occupying one position, means controlled by a train approaching the highway for rotating said member away from said one position in one direction at a constant speed through a variable distance which depends upon the speed of the train between

35 a first fixed point and a second fixed point, means effective when the train passes said second point for rotating said member in the opposite direction to restore said member to said one position, means controlled by said member and responsive to the distance away from said one position through which said member was moved for controlling the speed at which said member is restored to said one position, said speed being decreased as the distance through which said member is rotated away from said one position is increased, a highway crossing signal located adjacent said intersection, and means for setting said signal into operation when said member is restored to said one position, the parts being so proportioned that said member will be restored to said position at substantially the same interval of time before the train reaches the highway regardless of the speed of the 40 train.

45 7. In combination, a stretch of railway track intersected by a highway, a highway crossing signal located adjacent the intersection, timing means comprising a member normally occupying one position and an electric motor arranged to move said member away from said one position in response to rotation of said motor in one direction and to restore said member to said one position in response to rotation of said motor in the opposite direction, means effective when a train approaching said highway passes a first fixed point for energizing said motor in such manner that said motor is rotated in said one direction at a constant speed, means effective when the train passes a second fixed point for energizing said motor in such manner that said motor is rotated in said opposite direction, means controlled by said member and responsive to the position attained by said member in response to rotation of said motor in said one direction for controlling the speed at which said motor is rotated in said opposite direction, and means effective when said member has been restored to its one position for setting said signal into operation.

50 8. In combination, a stretch of railway track intersected by a highway, a highway crossing signal located adjacent the intersection, timing means comprising a member normally occupying one position and an electric motor arranged to move said member away from said one position in response to rotation of said motor in one direction and to restore said member to said one position in response to rotation of said motor in the opposite direction, means effective when a train approaching said highway passes a first fixed point for energizing said motor in such manner that said motor is rotated in said one direction at a constant speed, means effective when the train passes a second fixed point for energizing said motor

in such manner that said motor is rotated in said opposite direction, means controlled by said member for controlling the speed at which said motor is rotated in said opposite direction in such manner that the speed of said motor is decreased as the distance away from said one position through which said member was previously moved is increased, and means effective when said member has been restored to said one position for setting said signal into operation, the parts being so proportioned that said signal will be set into operation at substantially the same interval of time before the train reaches the intersection regardless of the speed of the train.

9. In combination, a stretch of railway track intersected by a highway, a highway crossing signal located adjacent the intersection, a member normally occupying one position, means for moving said member away from said one position through a variable distance determined by the speed of a train approaching a fixed point located in rear of said highway, a variable resistance, means controlled by said member for varying the value of said impedance in accordance with the distance away from said one position that said member is moved, means controlled in part by said resistance and effective when said train passes said fixed point for restoring said member to said one position at a speed which depends upon the value of said impedance at the time the train passes said fixed point, and means effective when said member has been restored to said one position for setting said signal into operation.

10. In combination, a stretch of railway track intersected by a highway, a highway crossing signal located adjacent the intersection, a member normally occupying one position, means for moving said member away from said one position at a constant speed while a train approaching said highway is traversing a fixed distance, a variable resistance controlled by said member, means controlled in part by said resistance and effective when said train has traversed said fixed distance for restoring said member to said one position, and means effective when said member is restored to said one position for setting said signal into operation.

11. In combination, a stretch of railway track intersected by a highway, a highway crossing signal located adjacent said intersection, a circuit including a variable resistance, means for varying the amount of said resistance which is included in said circuit in accordance with the speed of a train approaching a fixed point located in rear of said highway, and means for setting said signal into operation at a time interval before said train reaches said highway which depends upon the amount of the resistance

which is included in said circuit when said train passes said fixed point.

12. In combination, a stretch of railway track intersected by a highway, a highway crossing signal located adjacent said intersection, a circuit including a variable resistance, means for setting said signal into operation at a time interval before said train reaches said highway which depends upon the amount of the resistance which is included in said circuit when said train passes a fixed point, and means controlled by said train for varying the amount of the resistance which is included in said circuit when the train passes said fixed point in accordance with the speed of the train over a fixed distance in rear of said fixed point.

13. In combination, a stretch of railway track intersected by a highway, a highway crossing signal located adjacent said intersection, a circuit including a variable resistance, means for setting said signal into operation at a time interval before said train reaches said highway which depends upon the amount of the resistance which is included in said circuit when said train passes a fixed point, and means controlled in accordance with the speed of said train for varying the amount of the resistance which is included in said circuit when the train passes said fixed point in such manner that said signal will be set into operation at substantially the same interval of time before the train reaches the highway regardless of the speed of the train.

14. In combination, a stretch of railway track intersected by a highway, a highway crossing signal located adjacent said intersection, an electric motor comprising an armature and a field, a movable member operatively connected with said motor and normally occupying one position, means effective while a train approaching said highway is traversing a fixed distance for supplying said armature and said field with current in such manner that said member is moved away from said one position at a constant speed, means effective when said train has traversed said fixed distance for supplying said armature and said field with current in such manner that said member is returned to said one position, means controlled by said member for controlling the strength of the current which is supplied to the field of said motor while said member is being returned to said one position to control the speed at which said member is restored to said one position, and means for setting said signal into operation when said member has been restored to said one position.

15. In combination, a stretch of railway track intersected by a highway, a highway crossing signal located adjacent said intersection, an electric motor comprising an armature and a field, a movable member oper-

- atively connected with said motor and normally occupying one position, a first circuit for said field and a first circuit for said armature, said first circuits being so arranged that when these circuits are both closed said motor will move said member away from said one position in one direction at a constant speed, a second circuit for said field including a variable resistance and a second circuit for said motor, said second circuits being so arranged that when they are both closed said motor will move said member in the direction to restore said member to said one position at a speed which depends upon the amount of said variable resistance which is included in said second circuit for said field, means for closing both said first circuits when a train approaching said highway passes a first fixed point, means for closing both said second circuits when the train passes a second fixed point, means controlled by said member for varying the amount of the resistance which is included in said second circuit, and means effective when said member has been restored to said one position for setting said signal into operation.
16. In combination a stretch of railway track intersected by a highway, a highway crossing signal located adjacent said intersection, an electric motor comprising an armature and a field, a movable member operatively connected with said motor and normally occupying one position, a first circuit for said armature and a first circuit for said field, said first circuits being so arranged that when these circuits are both closed said motor will move said member away from said one position at a constant speed in one direction, means for closing both of said first circuits when a train approaching said highway passes a first fixed point, a variable resistance, a second circuit for said field including said variable resistance and a second circuit for said armature, said second circuits being so arranged that when they are both closed said motor will restore said member to said one position at a speed which depends upon the amount of said resistance which is included in said circuit, means for decreasing the amount of said resistance which is included in said second circuit for said field in accordance with the distance away from said one position in said one direction that said member is moved, means effective when the train passes a second fixed point for closing both of said second circuits, means for maintaining the amount of said resistance which is included in said second circuit for said field when this circuit becomes closed at the same value until said member is fully restored to said one position, and means for setting said signal into operation when said member has been restored to said one position, the parts being so proportioned that said signal will be set into operation at substantially the same interval of time before the train reaches the highway regardless of the speed of the train.
17. In combination, a first and second section of railway track, a highway intersecting said second section, a timing device comprising a rotatable shaft normally occupying one position and an electric motor operatively connected with said shaft for moving said shaft toward and away from said one position, means effective when a train enters said first section for energizing said motor in such manner that said shaft is rotated away from said one position at a constant speed, means effective when the train enters the second section for energizing said motor in such manner that said shaft is rotated toward said one position, a variable resistance for controlling the speed at which said motor moves said shaft toward said one position, means controlled by said shaft for controlling said resistance, and a signal located at said intersection and controlled by said shaft in such manner that said signal is set into operation when said shaft is restored to said one position, the parts being so proportioned that said signal is set into operation at substantially the same interval of time before the train reaches the highway regardless of the speed of the train.
18. In combination a stretch of railway track intersected by a highway, a highway crossing signal located adjacent said intersection, an electric motor comprising an armature and a field, a movable member operatively connected with said motor and normally occupying one position, a first circuit for said armature and a first circuit for said field, said first circuits being so arranged that when these circuits are both closed said motor will move said member away from said one position at a constant speed in one direction, means for closing both of said first circuits when a train approaching said highway passes a first fixed point, a variable resistance, a second circuit for said field including said variable resistance and a second circuit for said armature, said second circuits being so arranged that when they are both closed said motor will restore said member to said one position at a speed which depends upon the amount of said resistance which is included in said circuit, means for decreasing the amount of said resistance which is included in said second circuit for said field in accordance with the distance away from said one position in said one direction that said member is moved, means effective when the train passes a second fixed point for closing both of said second circuits, means for maintaining the amount of said resistance which is included in said second circuit for said field when this circuit becomes closed at the same value until said member is fully restored to said one position, and means for setting said signal into operation when said member has been restored to said one position, the parts being so proportioned that said signal will be set into operation at substantially the same interval of time before the train reaches the highway regardless of the speed of the train.

tially the same interval of time before the train reaches the highway regardless of the speed at which the train approaches the highway.

19. In combination, a first and a second section of railway track, a highway intersecting said second section, a track circuit for said second section including a first track relay, a track circuit for said first section including a second track relay and a front contact of said first track relay, a slow releasing relay controlled by a back contact of said second track relay and a front contact of said first track relay, a timing device comprising a member normally occupying one position and an electric motor for moving said member toward and away from said one position, means effective while a train approaching said highway is traversing a fixed distance for energizing said motor in such manner that said member is moved away from said one position at a constant speed, means effective when said train has traversed said fixed distance for energizing said motor in such a manner that said member is restored to said one position at a speed which depends upon the position to which said member was previously moved, a first contact which is closed when and only when said member occupies said one position, a signal relay; a circuit for said signal relay including a back contact of said slow releasing relay, a back contact of said first track relay, and said first contact; a second contact which is closed when said motor is stopped but which becomes opened when said motor is operating, a branch around said first contact in the circuit for said signal relay including said second contact, and a highway crossing signal controlled by said signal relay.
20. In combination, a stretch of railway track divided into a first, second, and third successive track sections a highway intersecting said second section, a track circuit including a track relay for each of said sections, the track circuit for said first section also including a front contact of the track relay for the second section, a slow acting relay provided with a circuit including a back contact of the track relay for said first section and a front contact of the track relay for the second section, an electric motor comprising an armature and a field, a rotatable shaft operatively connected with said armature and normally occupying one position, a first circuit controller controlled by said shaft and comprising a first and a second contact which are closed when said shaft occupies said one position but which become opened as soon as said shaft is moved away from said one position in said one direction and a third contact which is open when said shaft occupies said one position but which becomes closed as soon as said shaft is moved away from said one position in said one di-

rection, a second circuit controller controlled by said shaft and comprising a normally closed contact which becomes opened when said shaft is moved away from said one position in said one direction through a predetermined distance, a sleeve which is free to turn on said shaft, a spring for biasing said sleeve to one position on said shaft, means for rotating said sleeve by said shaft in opposition to the bias of said spring when said shaft is rotated in said one direction, a ratchet wheel fixed to said sleeve, a pawl cooperating with said ratchet wheel for preventing said spring from restoring said sleeve to said one position until said pawl is released, a solenoid for releasing said pawl, a contact arm attached to said sleeve, a variable resistance controlled by said arm and provided with a plurality of taps which cooperate with the arm in such manner that the amount of said resistance which is connected between one of said taps and said arm is decreased as said sleeve is rotated in response to rotation of said shaft in said one direction but that when said shaft has been rotated in said one direction to the position in which said second circuit controller is operated the total amount of said resistance is connected between said arm and said one tap, a centrifuge operatively connected with said motor, a contact controlled by said centrifuge in such manner that said contact is closed except when said motor is rotating at a speed which exceeds a predetermined value, a signal control relay, a highway crossing signal controlled by a front contact of said signal control relay; a circuit for said signal control relay including a back contact of said slow acting relay, a back contact of the track relay for said second section, and said first contact of said first circuit controller; a branch around said first contact of said first circuit controller in the circuit for said signal control relay including the contact controlled by said centrifuge; a fixed resistance, a first circuit for said field including a back contact of the track relay for said first track section, a front contact of the track relay for said second track section and said fixed resistance; a second circuit for said field including a back contact of the track relay for said first track section, a back contact of the track relay for said second track section, and the portion of variable resistance which is connected between said contact arm and said one tap when said circuit becomes closed; a first circuit for said armature including a back contact of the track relay for said first track section, a front contact of the track relay for said second track section, a front contact of the track relay for said third track section, and the normally closed contact of said second circuit controller; a second circuit for said armature including a back contact of the track relay for said first track section, a back contact of

the track relay for said second track section, and said third contact of said first circuit controller; the parts being so arranged that when said first circuit for said field and said first circuit for said armature are closed said 6 motor will rotate said shaft away from said one position but that when said second circuit for said field and said second circuit for said armature are both closed said motor will rotate said shaft toward said one position, 10 and a circuit for said solenoid including a back contact of the track relay for said first track section, a back contact of the track relay for said second track section, and said second contact of said first circuit controller. 15 21. In combination, a stretch of railway track intersected by a highway, a highway crossing signal located adjacent the intersection, timing means comprising a member normally occupying one position and an electric 20 motor arranged to move said member away from said one position in response to rotation of said motor in one direction and to restore said member to said one position in response to rotation of said motor in the opposite direction, 25 means effective when a train approaching said highway passes a first fixed point for energizing said motor in such manner that said motor is rotated in said one direction at a constant speed, means effective when the 30 train passes a second fixed point for energizing said motor in such manner that said motor is rotated in said opposite direction, means controlled by said member and responsive to the position attained by said member in 35 response to rotation of said motor in said one direction for controlling the speed at which said motor is rotated in said opposite direction, means effective when said member has been restored to its one position for setting said signal into operation, and means effective when the train has passed the highway for stopping the operation of said signal.

In testimony whereof I affix my signature.

BRANKO LAZICH.
